SHAVING APPLIANCE

David O. Brant, Canoga Park, Calif.

Application January 17, 1939, Serial No. 251,368

8 Claims. (Cl. 30—49)

The present invention relates to safety razors and particularly to a double edged band razor, both edges of which are of an endless character.

First, it is an important object of the invention to improve upon band razors wherein two cutting edges are provided which are circularly continuous.

Secondly, it is an important object of the invention to improve upon and simplify the holding means for the razor, whereby the blade is securely and accurately maintained in its operative position.

Thirdly, it is an important object of the invention to improve upon the means for and method of applying the razor blade to the guard member.

Further important objects of the invention are to provide an improved guard member; to provide a continuous shaving element composed of a plurality of like parts; and to provide a razor that can be made more cheaply by eliminating the usual handle.

A further object of the invention is to provide a razor that can be made of lighter materials, and which are less expensive and more easily handled, and may be discarded after use, without compunction.

Viewed as a method, the invention further relates to improved steps for clamping in place in the mounted position, one or more elongated, resilient blades, around a support, with the end portions of such blade or blades directed toward each other in adjacent or else abutting relations.

With the foregoing and other objects in view, the invention consists, in general, of certain novel details of construction and combination of parts hereinafter fully described, illustrated in the accompanying drawing and particularly pointed out in the appended subject matter claimed.

In the accompanying drawing, wherein is shown a preferred embodiment of the invention, as well as alternate generic embodiments.

Fig. 1 is a perspective view of the preferred species.

Fig. 2 is a fragmental section, taken on line 2—2 of Fig. 1.

Fig. 3 is a perspective view of the clip whereby the razor blade is applied to the holder.

Fig. 4 is a transverse section.

Fig. 5 is an elevational view of the blade.

Fig. 6 is an elevational view of one of a series of blades from which a continuous blade is constructed.

Fig. 7 is an alternate embodiment showing in plan a holder and blade formed from the quadrant of a circle.

Fig. 8 is a section taken on line 8—8 of Fig. 7, and,

Fig. 9 is a section taken on line 9—9 of Fig. 7.

Referring in detail to the drawing, the blade holding member 9 includes a peripheral annular wall or ring 10, the length, that is to say, the axial dimension of which is somewhat less than the breadth of the double-edged blade 11 which is provided to be supported thereby. Said blade holding member also includes a central rib or internal cross wall 12 united thereto, or made integral therewith as shown in the drawing. Said cross wall 12 is shown located at the mid-length of the ring, axially considered.

The blade 11 is a flexible steel band capable of being flexed around the ring 10, and having a slot 13 in a parallel adjacent relation to each of its end edges. Each of the side edge portions of said blade is beveled at 15 along its outer (when mounted) face to form a sharp cutting edge. Along each of its side edges the annular member 10 is rounded at 16, these rounded edge portions forming guards which are properly juxtaposed in relation to the cutting edges of the applied blade 11 to cause the device to operate effectively without cutting the face of the user.

The cross wall 12 occupies all the space enclosed by the ring 10 and forms a convenient hand hold for the person using the appliance, as indicated by the dotted lines, 10h delineating a portion of a human hand in Fig. 1. Avoiding the necessity of attaching a separate handle means to the device is an important feature of the invention.

In order to hold the blade 11 in its mounted position a bendable metallic clip 20 is provided, which is preferably shaped at first as shown in detail in Fig. 3, where said clip is shown as consisting of a strap of metal having an angularly bent central portion 21 furnished at each side with a foot portion 22 which has underlying it a terminal flange or toe portion 23. Each of these terminal flanges is directed towards its mate and is in a spaced, substantially parallel relation to the foot portion 22 of which it is a continuation.

The ring 10 is of a sufficient thickness to provide for forming in the midwidth portion of its outer periphery a depression or recess 24, and when the blade 11 is mounted upon the ring it is so positioned as to bring its slotted end portions in an overlying relation to said recess 24, the foot flanges 23 of the clip 20 being at that time hooked into said slots so as to cause said clip to form a connecting link between the end

portions of the blade after the latter has been bent to a circular shape. Then the user will bend the two sides of the angular part 21 into a closer relation to each other, thus drawing the blade snugly against the exterior periphery of the ring. Thereupon the bent together portions of the clip portion 21 will be collectively bent down to the position shown in Fig. 1, thus forming a means whereby the blade is locked in place around the ring. It is necessary to provide means to prevent the blade from displacement in an edgewise manner. For this purpose the ring is provided with a plurality of exteriorly projecting studs 25 which are circumferentially spaced in correspondence with the spacing of a series of short slots 26 formed along the midwidth of the blade. Said studs 25 project through said slots 26 when the blade is in its mounted position, the slots being long enough to allow clearances requisite for the tractioning action of the clip 21 upon the ring, when said clip is used to lock the ring in place in the manner which has been explained.

If desired, instead of the single long blade 11 shown in Fig. 5 being used, a plurality of shorter blades, each shaped as the blade 30 of Fig. 6, 25 may be employed, at least one of the slots 26 being formed in such blade, and when only one of these slots is provided it should be located in the mid length portion of the blade. In order to secure these blades 30 in place their end portions are secured to each other by additional clips 20, the ring 10 being provided with additional recesses 24 where the end portions of the short blades 30 meet.

Whether a single blade or more than one is mounted upon the member 9 the blade ends are brought as nearly as possible into an abutting relation.

The ring 10 has a plurality of hair and lather admission slots 31 which are in an adjacent parallel relation to its rounded rims 16. The clearance afforded by said slots is made as nearly continuous as practicable, said slots being separated by narrow intact wall portions 32. The mounting means 9 is I-shaped when viewed in any diametrical cross section.

In Figs. 7, 8 and 9 is shown a modified, arcuately shaped guard rim 49 having a web or finger-hold portion 41 located at its concave side and uniting its end portions to each other. In this form of the invention a conventional Gillette blade is shown held in its attached position by means of an arcuate outer clamping plate 45 which is not only arcuate as to its length but is outwardly convexed transversely. At its mid length and mid width said plate 45 carries an internally projecting threaded stud 46 which projects through an apertured boss 47 formed on the rim 40. On to the projecting portion of said stud is screwed a milled nut 48 to clamp the attached blade in place. Said plate 45 also carries in a spaced relation to each of its ends, two internally projecting mounting studs 45s. These studs fit within and project thru holes provided for them in the rim 40.

Although a Gillette blade is shown in Fig. 7 mounted upon the device, yet obviously the form of the device shown in this view may be adapted for having mounted upon it the blade shown in Fig. 6.

The appliance shown in Figs. 7, 8 and 9 is also furnished with rounded safety rim portions or guards. However these guards, 16a, are of a serrated or castellate character to provide additional channels for the hair and lather. This

feature may, if desired, be incorporated into the embodiment of the invention first described.

In the segmental form of the device shown in Fig. 7, the web 41 is arcuately cut away along its inner side thus affording a lozenge shaped opening 49 adjacent to the stud 46, this opening affording a clearance to enable the user to readily apply and remove the nut 48.

The method of using the clips 20 to attach one or more blades in the embodiment of the invention shown in Figs. 1 to 4 has already been described, but a few words of explanation need to be added as to the advantages possessed by and the way of using the blade mounting means shown in the remaining views.

The blade 30 is not only provided with a central opening to receive the threaded stud 46, but is also provided with openings spaced properly for receiving the studs 45s, the latter studs being sufficiently long to hold the blade in place upon the detachable plate 45, preparatory to clamping said plate in place. In applying the blade 30, the user will grasp said blade in an endwise manner between thumb and finger and will apply thereto enough pressure to bow it into the same direction that it will assume when mounted. While holding the blade thus he may readily slip its central apertured part over, first the central stud 46 and then its lateral apertured portions over the studs 45s, whereupon the plate 45, together with the blade 30 may be put into the mounted position and secured in place by screwing the nut 48 in place. The arcuate web 41 forms a convenient handle means for using this form of the invention as a shaving implement.

In both embodiments of the invention the peripheral portion of the appliance has an inwardly directed web which serves as a hand-hold and hence avoids the expense and additional bulk incident to the provision of a conventional handle. Also, in the first embodiment described, having an internal handle means leaves the entire circumference of each cutting edge unobstructed and available for use in shaving.

The slots 31 may be provided with indicating numbers 55. Thus numbered they may be used to indicate to the shaver the amount of blade length employed in a shaving operation, so that when one portion of the circumference of the blade has been used, and consequently becomes more or less dulled, the portion thereof adjacent to the next slot in the series may be used for the next shave, until all portions of the blade have been utilized. Other indicating means, for example, differently colored portions may be employed either on the holder or blade, if desired; but progressively numbering the slots is thought to be as good a means as any for carrying out the stated purpose, the slots on one side of the web being furnished with higher numbers than those on the opposite side thereof. Or spaced numbers 56 may be placed on the blade for the same purpose. A few examples only, of these indicating numbers, are shown in the drawing.

It should be understood that the present disclosure is for the purposes of illustration only, and that this invention includes all modifications and equivalents which fall within the scope of the subject matter claimed.

There is claimed:

1. A ring shaped guard member provided with a rounded side edge portion and having a manually grippable cross wall disposed at the mid-

length thereof, a flexible razor blade, and means to mount said blade on said guard member with the end edges thereof in abutting non-overlapping relation, there being a plurality of hair and lather admission slots in said guard member in an adjacent parallel relation to said rounded edge.

2. A ring shaped guard member, a flexible razor blade, and mounting means on said member for said blade, said mounting means having a circumferential continuity, said blade having apertures adjacent the ends thereof, and said mounting means including a flexible connection having hooks engageable in said apertures, said connection being manually collapsible for drawing the ends of said blade thru the medium of said hooks into an abutting circumferential continuity, there being a recess in the peripheral portion of said guard member wherein the inner ends of said hooks are housed whereby the diametrical extent of said blade is maintained substantially uniform.

3. A cylindrically shaped ring section having a circumferentially arranged series of centering devices projecting outwardly from the outer face thereof, a flexible blade having a series of apertures to register with said centering devices when said blade is placed around said section, there being slots in said blade adjacent the ends thereof, and means extendable thru said slots for drawing the ends of said blade into an abutting relation.

4. The subject matter of claim 3 and, a manually grippable cross wall disposed at the mid-length of said section, there being a series of openings in the end portions of said section, through which lather and hair is adapted to move during a shaving operation, said cross wall additionally serving as a catch for said lather and hair.

5. In a safety razor, a mounting member having an exterior surface of a curved character to form a seat for a razor blade, an elongated resilient blade occupying said seat, said blade having

portions adjacent to its ends affording shoulders, and a bendable clip having a pair of limbs, portions of which are in engagement with said shoulders to maintain the end portions of said blade in 5 an adjacent relation to each other, the part of said clip between said end portions being folded upon itself at such time to hold the attached blade in its contracted mounted position.

6. The subject matter of claim 5 and, said 10 blade having apertures through it, edge portions of which constitute the aforesaid shoulders.

7. In a safety razor, a substantially circular mounting member, an elongated blade having a cutting edge, means whereby said blade is attached to said mounting member in a circumferential exterior relation, said member having around its ends circular guards positioned to cooperate with the cutting edges of the mounted blade, a cross wall located at substantially the 15 mid length of said member, said cross wall being positioned to form a hand hold for use in applying any portion of said cutting edge to the face of the user in shaving, and means to secure said blade in its aforesaid mounted position.

8. In a safety razor, a mounting member having a substantially cylindrical outer wall, an elongated blade having a cutting edge, and means whereby said blade is maintained in a mounted position upon said wall in a circumferential exterior relation thereto, said means including a clip whereby opposite end portions of said blade are connected together in a juxtaposed relation, said mounting member having around its end portion a circular guard positioned to cooperate with the adjacent cutting edge of the mounted blade, said mounting member including a web portion located at substantially its mid length and positioned to form a hand hold whereby all portions of the cutting edge of said blade may 20 be used in shaving, the aforesaid cylindrical wall having through its end portion a series of adjacent apertures positioned to admit lather and shaved off hair when the appliance is in use.

DAVID O. BRANT.
